UNITED STATES PATENT OFFICE.

EMIL R. DRAVER, OF STILLWATER, MINNESOTA, ASSIGNOR, BY MESNE ASSIGNMENTS, OF ONE-HALF TO MARIE L. DRAVER, OF SAME PLACE.

DUST-COLLECTOR.

SPECIFICATION forming part of Letters Patent No. 608,587, dated August 9, 1898.

Application filed January 25, 1897. Serial No. 620,588. (No model.)

To all whom it may concern:

Be it known that I, EMIL R. DRAVER, a citizen of the United States, residing at Stillwater, in the county of Washington and State 5 of Minnesota, have invented certain new and useful Improvements in Dust-Collectors; and I do hereby declare the following to be a full, clear, and exact description of the invention, such as will enable others skilled in the art 10 to which it appertains to make and use the same.

My present invention has for its object to provide an improvement in dust-collectors of the general type illustrated in my pending 15 applications, Serial Nos. 611,185, 611,186, and 611,187, all filed of date November 5, 1896, and entitled "dust-collectors."

My said present invention is most closely related to and is intended more particularly 20 as an improvement on the form of dust-collector disclosed in my said pending application Serial No. 611,185.

To the ends above noted my present invention consists of the novel devices and combinations of devices hereinafter described, and 25 defined in the claims.

My present invention is illustrated in the accompanying drawings, wherein, like notations referring to like parts throughout the 30 several views—

Figure 1 is a view, partly in side elevation and partly in longitudinal section, through my improved machine or dust-collector shown as organized for use as part of or in connection with a middlings-purifier. Fig. 2 is a 35 transverse vertical section taken substantially on the irregular line X² X² of Fig. 1. Fig. 3 is a transverse vertical section taken through a portion of the machine, substantially 40 on the line X³ X³ of Fig. 1. Fig. 4 is a longitudinal section through a portion of the machine, taken substantially on the line X⁴ X⁴ of Fig. 3. Fig. 5 is a detail view in section, taken substantially on the line X⁵ X⁵ of 45 Fig. 3. Fig. 6 is a perspective view, with some parts broken away and others shown in section, of substantially that part of the machine which is illustrated in Figs. 3 and 4. Fig. 7 is a view, partly in side elevation and partly 50 in section, with some parts broken away, showing a portion of the machine and illus-

trating means for automatically opening and closing relief-ports which open to the cells or stalls; and Fig. 8 is a transverse section on the line X⁸ X⁸ of Fig. 7.

55

The numeral 1 represents the frame or casing of the middlings-purifier.

The numeral 2 represents one of the sieves of the purifier, which receives a vibratory motion from the transverse power-driven 60 shaft 3 through intermediate mechanism. (Not shown.) This sieve 2 receives the unpurified stock from a feed-hopper or spout (not shown) and discharges into a delivery-spout 4.

65

The numeral 5 represents the main section of the closed or tight wall-chamber above the sieves of the purifier, and the numeral 6 represents the clean-air chamber at the top of the machine.

70

The numerals 7 and 8 represent, respectively, the fan and fan-case, (shown as mounted in the top wall of machine,) which fan is of the proper construction to operate as a suction-fan for producing forced currents of air 75 through the machine.

The numeral 9 represents a series of transverse partitions connected and closed at their ends by the side walls of the chamber 6, which partitions 9 are spaced apart from each other 80 a suitable distance to form a series of cells or stalls 10. At their upper ends these cells 10 are partially closed by means of horizontal top boards 11, provided with air-passages 12, which are adapted to be opened and closed 85 by means of hinged or pivoted cut-off gates 13. Preferably these gates are under a yielding strain which tends to hold the same open, and, as shown, this is accomplished by means of springs 14, applied as best shown in Fig. 5. 90 The upward or opening movement of the gates 13 may be variably intercepted by means of a stop-bar 15, mounted for sliding movement longitudinally of the machine through suitable keepers 16, secured on the upper 95 face of the continuous horizontal partition formed by the top boards 11, which bar 15 is provided with inclined or cam surfaces *a*, corresponding in number to the number of gates 13 and co-operating as stop-surfaces one 100 with each of said gates 13. The bar 15 may project from one end of the machine-frame

and be terminated in a handpiece, by means of which it may be operated at will for securing the bar 15 in its different longitudinally-adjusted positions. The cells 10 are closed at their lower ends by flexible bottoms composed of a center board or plate 17 and flexible joint-strips 18, connecting said board 17 to the side walls 9 of said cells.

The center boards 17 are each provided with a series of large perforations or holes 19 of the proper size to receive the lower open ends of a corresponding series of collecting-tubes 20, which are mounted in the cells 10. The said tubes 20 are made of flannel or other suitable material adapted to serve as a collecting-surface. In the construction shown the upper ends of the collecting-tubes 20 are closed by means of disks 21, which are secured to said tubes and to rigid supporting-bars 22, running transversely of the machine, but longitudinally of the cells or stalls 10, with their ends supported from the side walls of the chamber 6.

The center boards 17 of the flexible bottoms are vertically raised and then allowed to drop, so as to shake or rap the series of collecting-tubes to which they are attached, each by an independent lifting device. Each of these lifting devices, as preferably constructed, comprises a pair of vertically-movable lifting-rods 23, the lower ends of which are secured one to each end of the center board 17 for that cell, and the upper portions of which extend through suitable passages in the bar 22 and the top board 11. The upper ends of these lifting-rods 23 are pivotally attached to horizontal lever-arms 24^b, fixed on a transverse rock-shaft 25. The said shaft 25 is also provided with a depending lever-arm 24^b for rocking said shaft and shaking the collecting-tubes 20, as will later more fully appear. On the lifting-rods 23 are springs 26, which are compressed between the supporting-bar 22 and pins 27, passed through said rods 23. These springs 26 serve normally to force the bottom or center board 17 downward to its extreme lowermost position, thereby distending the tubes 20 to their extreme length.

To operate the lifting devices just described and to close the cut-off gates in succession and during the intervals at which the corresponding or co-operating lifting devices are operated, I employ an endless traveler, preferably in the form of a sprocket-chain 28, which runs over suitable sprocket-wheels 29, mounted on shafts 30, one at each end of the machine. As shown, the sprocket-chain 28 runs over and under a skid or guide 31, which is properly supported in a fixed position between and in line with the sprockets 29. At one or more points the chain 28 is provided with a gate-closing device, preferably formed by several inwardly-projecting blocks 32, secured to adjacent links of the chain. Said chain is also provided with blocks 33, which project outward from the chain and are adapt-

ed to engage the lower ends of the rock-shaft levers 24^b. There are preferably a sufficient number of the gate-closing lugs 32 to cause the gate 13 when once closed to remain closed long enough to permit the precipitation of the dust from the tubes 20, and, as shown, there are three of the rock-shaft lugs 33, so arranged with reference to said blocks 32 as to cause a particular lifting device to be operated three times during the interval that the cut-off gate 13 is held closed by the lugs 32. It will be understood, of course, that the closing of the cut-off gates 80 is caused by the sliding engagement therewith and downward pressure thereon of the blocks 32 and that the skid or guide 31, over which the chain is passed, serves to prevent the chain from yielding or moving upward under any tendency which the cut-off gates may have to open or to remain open. When one of the blocks 33 engages the free end of a particular lever 24^b, said lever will be rocked slowly and the bottom or center board 17 of the flexible bottom of the corresponding cell 10 will be raised to its limit, at which point the said block 33 will pass from under the lower end of said rock-lever arm 24^b, and the springs 26 will then be permitted to act and throw said board 17 downward to its extreme limit with a sudden impulse, thereby simultaneously rapping or jarring all of the collecting-tubes of that particular cell. As shown, there are six collecting-tubes, arranged transversely of the machine in each cell or stall 10.

Running longitudinally of the machine and located one under each transversely-adjacent pair of collecting-tubes 20 is a long hopper-like trough formed by pairs of converging deflecting-plates 34, which terminate short of each other. There are three of these hopper-like troughs, and, taken together, they form a substantially air-tight horizontal partition below the tubes 20, except for the longitudinal openings left between the converging ends of the deflecting-plates 34. As shown, each longitudinal hopper thus formed is divided by a longitudinal vertical partition 35, the ends of which are fixed to the machine-frame.

Immediately below each of the longitudinal hoppers just described is a longitudinally-extended trough 36, which is open at its upper portion and has its upper edges spaced apart from the converging edges of the deflecting-plates 34, of which said hopper-like troughs are formed, to leave longitudinally-extended air-passages between said parts. In each of the dust-troughs 36 is a reciprocating conveyer, formed by a reciprocating partition-bar 37, set edgewise and provided on each side with a series of loosely-pivoted shovels 38, that are free to move in one direction and, as shown, are held against movement in the other direction by stop-pins or projections 39, carried by said bar 37. It will be noted that the reciprocating bar 37 is positioned to work directly under the bar 35

and coöperates therewith to form a substantially air-tight partition dividing the dust-trough longitudinally into two compartments. The purpose of this partition will be noted later on. At the rear of the machine the dust-troughs 36 terminate in small discharge-hoppers 40, provided with gravity-held hinged gates 41. A common discharge-trough 42 receives from all three of said hoppers 40. As is evident, when the bar 37 of the reciprocating conveyer has moved toward the front of the machine the pivoted shovels 38 will slide freely over the dust collected in the troughs, while when said bar is moved toward the rear of the machine said shovels will engage and positively carry the dust rearward toward the discharge-hoppers 40. The required reciprocating motion is given to the reciprocating conveyers and, as shown, simultaneously to all three of the same by means of the following device: A rod 43 is passed transversely through the forwardly-projecting ends of all of the reciprocating bars 37. 44 is a transverse rock-shaft mounted in suitable bearings on the machine-frame and provided with two or more depending arms 45, the free ends of which are pivoted on the rod 43. The rock-shaft 44 is also provided at one end with a forwardly-projecting arm 46, to the free end of which the lower end of a pitman-rod 47 is pivoted. The upper end of the pitman-rod 47 is pivoted to a crank-pin carried by a sprocket 48 on the forward member of the chain-shafts 30. In the construction shown motion is imparted to the sprocket-wheel 48 through a chain 49, which passes over the same and over another sprocket 50 on the shaft 3. This shaft 3 receives motion in some ordinary manner. (Not shown.)

I have found by actual experience with machines of this class that it is practically impossible to entirely shut off the forced draft through the cells and collecting-tubes, and that when this is attempted there will be more or less leakage through the cut-off devices and other parts of the machine, and that this leakage will permit a slight suction from the fan, which will tend to hold particles of the dust against the surfaces of the collecting-tubes or other collecting media, thus materially interfering with the proper precipitation and collection of the dust. To obviate this defect, I in some cases provide open relief ports or passages formed in the side walls of the cells, as shown at 51 in Figs. 1 to 6, inclusive. These passages 51, when designed to be left open during the time that the dust is being collected by suction, should be only so large and no larger than is necessary to relieve the tubes from the suction due to leakage through the cut-off devices when closed. However, I prefer to employ port-openings which are larger than those illustrated in Figs. 1 to 6, inclusive, and provide in connection therewith means for automatically closing the same while the dust is being collected by suction and for opening the

same while the dust is being precipitated from the collecting-tubes. This latter construction is illustrated in Figs. 7 and 8, in which the port-openings or relief-ports 52 are adapted to be opened and closed by means of hinged valves or port-gates 53, that are normally held closed by gravity.

As shown, the valves 53 are provided with inwardly-projecting pins 54, that are adapted to be pressed by the foot portion of a vertically-movable plunger 55, working through a keeper 56 and pivoted at its upper end to the free end of a cam-lever 57. This cam-lever 57 is pivoted to one of the cell top boards 11 and is provided with an inclined or cam portion 58, which works through a suitable slot cut in said board 11 and normally projects upward into the path of cam-blocks 59, some of which are formed on the bottoms of the lugs or blocks 33, that operate the lifting devices, and others of which are carried by adjacent links of the link chain. These cam-blocks 59 operate on the cam portion 58 of the lever 57 and positively hold the same downward and the valve 53 open during the time that the cut-off gate 13 is in a similar manner held positively closed by the action of the cam-blocks 32. The weight of the valve or port-gate 53 is sufficient to automatically close itself and hold the parts 55 57 58 upward in their normal positions when the cam-surface 58 is not acted upon by the cam-blocks 59.

Briefly summarized, the action of the machine as an entirety is substantially as follows: Under the updraft suction from the fan 7 the dust from the sieve 2 will be drawn upward and will gain entrance to the lower open ends of the collecting-tubes 20 by a winding course over the upper edges of the dust-troughs 36 and under the converging edges of the deflecting-plates 34, as indicated by arrows marked on Fig. 2. In taking this winding course a very large portion of the dust will be precipitated directly into the dust-troughs by the deflecting action of the deflecting-plates 34. Right here it is important to note that the vertical partition formed by the fixed bar 35 and the reciprocating bar 37 serves to prevent the currents of air which enter from the opposite sides of the trough from coming together or uniting within the trough. If these currents of air that enter from the opposite sides of the trough were allowed to come together within the trough, they would produce vortices or whirling updrafts, which would carry much of the dust which is precipitated into the trough on upward into the collecting-tubes. The dust-laden air thus partially cleaned or lightened by the precipitating action of the deflecting-plates 34 will be drawn upward into the collecting-tubes 20 and the dust collected on the inner surfaces of the same, while the cleaned air will pass through said collecting-tubes and be drawn on upward and discharged through the fan.

As already described, the cut-off gates of the series of cells will be closed in succession and the series of collecting-tubes in a given cell will be rapped or jarred while the cell is closed. The dust precipitated from the collecting-tubes under this rapping or jarring action will fall onto the deflecting-plates 34, or, in other words, into the hoppers formed by said plates 34, and will be thereby directed into the dust-troughs 36, from whence it will be discharged by the reciprocating conveyers in a manner already fully described.

It is desired to recall attention to the fact that the cut-off gate, located one in the delivery end of each cell, is held positively closed during the time that the rapping of the tubes contained in the said cell and the precipitation of the dust therefrom takes place. This is an important feature of construction, as it enables a much better and tighter joint to be made around the cut-off device, thus greatly reducing the necessary amount of leakage.

Returning now to the relief-port feature of my invention and briefly analyzing the principle involved in the same, it will be seen that from a broad point of view any form of collecting medium may be employed in connection with any form of blast or forced-air device which will cause the collection of the dust on the collecting medium, it being only necessary that some form of cut-off device be employed which is adapted to relieve said collecting medium from the action of said forced-air device except as due to leakage and that one or more relief-ports be provided through such portion of the machine as will give a supply or escape of air to relieve the collecting medium from the forced current of air due to leakage. As already indicated, the relief-ports should be of such size and number that their aggregate opening is in excess of that of the leakage-passages. Hence it is obvious that to obtain the greatest economy in the use of air the relief-ports should be opened and closed in the manner illustrated in Figs. 7 and 8 or in some other suitable manner. As has also been indicated before, the strength of the draft of air through the collecting-tubes may be varied by adjusting the stop-bar 15 longitudinally of the machine, so as to cause its cam portions to variably intercept the upward opening movements of the cut-off gates 13. It is of course obvious that the opening movements of all of the cut-off gates are simultaneously varied by one and the same movement of the longitudinal stop-bar 15.

From the foregoing statements it is thought to be evident that various alterations in the details of construction above specifically illustrated may be made without departing from the spirit of my invention. For example, the collecting-tubes 20 instead of being fixed at their upper ends and jarred or moved from their lower ends might be fixed at their lower ends and jarred or moved from their upper

ends. Again, the shovels 38, which are pivoted to the opposite faces of the reciprocating conveyer-bar 37, might be limited in their pivotal movement in one direction by means other than the stops 39 on said bar. One modification which I have contemplated consists simply in giving the shovels sufficient forward pitch so that they may rest directly upon the bottom of the trough, in which case the action of the shovels would be substantially identical with that of the construction specifically described.

The term "traveler" is used to indicate a body that is mounted to move over or pass the series of gates or cut-off devices whether mounted for endless or reciprocating movement.

What I claim, and desire to secure by Letters Patent of the United States, is as follows:

1. In a dust-collector, the combination with a series of cells, of dust-collecting media in said cells, a series of hinged cut-off gates one in the head of each cell, normally held in their open positions, an endless traveler provided with projecting cam lugs or blocks which engage and positively close said cut-off gates, and a fixed skid or guide, under and over which said endless carrier runs, substantially as described.

2. In a dust-collector, the combination with the collecting medium and means for producing a forced circulation therethrough, of a device or devices for cutting off the forced circulation through said collecting media, and a relief port or ports which compensate for leakage and relieve said collecting media from forced currents of air, while the cut-off devices are closed, substantially as described.

3. In a dust-collector, the combination with the collecting medium and means for producing a forced circulation of air therethrough, of a device or devices for cutting off the forced circulation of the air through said medium, relief-ports which compensate for leakage and relieve said collecting medium from forced currents of air, while said cut-off devices are closed, and a valve for each of said relief-ports, normally closed but automatically opened when said cut-off device is closed, substantially as described.

4. In a dust-collector, the combination with a suction-fan a series of cells and dust-collecting media therein, of cut-off devices for closing the outlets of said cells, and relief-ports to compensate for leakage and relieve said collecting media from forced drafts, when said cut-off devices are in their closed positions, substantially as described.

5. In a dust-collector, the combination with a suction-fan, a series of cells and dust-collecting media therein, of cut-off devices for closing the outlets of said cells, relief-ports to compensate for leakage, and automatically-operated valves opening and closing said relief-ports, substantially as and for the purpose set forth.

6. In a dust-collector, the combination with

a suction-fan, a series of cells and dust-collecting media therein, of cut-off devices for closing the outlets of said cells, relief-ports to compensate for leakage, valves opening and closing said relief-ports, and an endless traveler operative to open and close said cut-off devices and said relief-port valves, in reverse order, substantially as and for the purposes set forth.

10 7. In a dust-collector, the combination with a suction-fan, a series of cells, a series of collecting tubes or pockets in said cells and corresponding series of tube shaking or rapping devices, of independently-hinged cut-off gates in the heads of said cells, relief-ports to compensate for leakage, valves in said relief-ports, and an endless traveler, operative to open and close said cut-off gates and said port-valves, in reverse order, and to operate 15 said shaking or rapping devices while the corresponding cut-off gates are closed, substantially as described.

8. The combination with a cell and a dust-collecting medium therein, of a cut-off device 20 or gate in one end of the same, under yielding strain to remain open, and an adjustable 25

stop for variably intercepting the opening movement of said cut-off device or gate, substantially as described.

9. The combination with a series of cells 30 and dust-collecting media, of individual cut-off devices or gates in the heads of said cells, under yielding strain to remain open, and an adjustable stop device for simultaneously varying the normal open positions of a series 35 of said cut-off devices or gates, substantially as described.

10. The combination with the series of cells and dust - collecting media therein, of the hinged cut-off gates in the heads of said cells, 40 under strain to normally open, and the longitudinally-adjustable stop-bar provided with cam or inclined surfaces which serve to variably intercept the opening movements of said cut-off gates, substantially as described. 45

In testimony whereof I affix my signature in presence of two witnesses.
